UNITED STATES PATENT OFFICE

EWALD UFERT, OF TRENTON, NEW JERSEY

DESIGN FOR A COMBINED LAMP AND RADIOCABINET

Application filed June 10, 1931. Serial No. 40,159. Term of patent 14 years.

To all whom it may concern:

Be it known that I, EWALD UFERT, a citizen of the United States, residing at Trenton, in the county of Mercer and State of New Jersey, have invented a new, original, and ornamental Design for a Combined Lamp and Radio Cabinet, of which the following is a specification, reference being had to the accompanying drawings, forming part thereof.

In said drawings:

Figure 1 is a front elevation of my combined lamp and radio cabinet showing my new design.

Fig. 2 is a plan view thereof.

Fig. 3 is a side elevation of my combined lamp and radio cabinet.

I claim:

The ornamental design for a combined lamp and radio cabinet, as shown.

EWALD UFERT.
